FIG. 3

UNITED STATES PATENT OFFICE

2,476,723

POSITIVE GRIP FILLING MACHINE

Max Goldberg, New York, N. Y.

Application April 11, 1946, Serial No. 661,400

2 Claims. (Cl. 226—19)

1

This invention relates to a machine for filling the casings of articles, particularly those made of non-porous fabric, skins, etc.

An object of this invention is to provide a machine for filling fibrous materials by movable gripping jaws having one-way feeding teeth which positively grip and feed the fibrous material into non-porous or porous fabric casings.

Another object of this invention is to mount the feeding jaws on pivotally mounted links of equal length so as to cause the gripping jaws to move and feed while in parallel relation to each other.

Another object of this invention is to pivotally mount the feeding jaws on the upright legs of a slidable and inverted U-shaped frame to permit the fibrous material to be fed to the feeding jaws between the upright legs of the slidable frame.

Another object of this invention is to provide a rotatable cam for actuating the frame downwardly and to provide tension springs for raising the frame with a quick return motion.

Another object of this invention is to provide fixed cam mechanisms which causes lateral movements of the opposed feeding jaws.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference will designate corresponding parts throughout the several views, in which:

Figure 1 is a front elevation of the filling machine, the housing being partly broken away to show the interior of the mechanism.

Figure 2 is an end view of the filling machine shown in Figure 1, the housing being partly broken away.

Figure 3 is a cross-sectional view, the section being taken as on line 3—3 in Figure 1.

Figure 4 is an enlarged fragmentary view of a mechanism which reciprocates the feeding jaws in parallel relation.

In the illustrated embodiment of the invention, the numeral 10 indicates a gripping and feeding mechanism for fibrous material. The mechanism 10 comprises a mounting plate 11, preferably supported in an upright position on an angular extension 12.

An inverted U-shaped frame 13 is mounted in bearings 14 for vertical sliding motion on the mounting plate. Tension springs 15 secured at

2

their upper ends to studs 16, and at their lower ends to the horizontal bar 17 of the frame 13, support the frame in uppermost position.

An open face type disk cam 20 is fixed to a shaft 21 by a key 22. The shaft 21 is rotatably mounted in a bearing 23 secured to the mounting plate 11. The cam 20 has an abrupt radially directed face portion 24. The cam contacts an elongated extension 25 on the horizontal bar 17 of the U-shaped frame 13.

In practice, the length of the radially directed cam face 24 is less than the length of the elongated extension 25 to assure contact of the upper or contact point of the extension 25 with the cam 20 and avoiding contact between the cam and the horizontal bar 17 of the frame 13.

The cam 20 is of the open face disk type and may be taken as representing any suitable means for actuating the frame 13 toward the lower portion of the mounting plate 11.

The cam 20 imparts a downward motion to the frame 13 for every revolution of the shaft, and the tension springs 15 raise the frame when released by the cam. The frame is raised with a quick return motion due to the radial face 24.

The inverted U-shaped frame 13 has vertically positioned legs 27. A gripping and feeding jaw 28 having an elongated upper bar-shaped portion 29 is pivotally mounted on each of the legs 27 by links 30. The links 30 are of equal length between the centers of the pivots 31. The legs 27 and bar-shaped portions 29 and the links 30 form a jointed rectangular frame whereby the gripping jaws are constrained to move in constant parallel relation with the legs 27 while the distance between the bars 29 and legs 27 is varied at the uppermost and lowermost ends of each stroke.

Each gripping and feeding jaw 28 comprises an overhanging lower toothed portion 32 having teeth 33. The teeth 33 have horizontal lower faces and inclined sides. The teeth are positioned to face each other and to be in spaced-apart relation. As shown in Figure 1, it will be seen that the oppositely coacting teeth 33 on opposite jaws 28 have sides which lie in the same horizontal plane and have downwardly converging sides so as to cause the teeth to feed one-way, in a downward direction.

In the lowered position shown in Figure 1, the upper ends of the gripping and feeding jaws 28 are in spaced relation with projections or lugs 34 extending from the legs 27 of the frame 13. The lower faces of the teeth 33 of the opposite jaws 28 are in alignment in horizontal planes.

A housing or chute 35 having a front wall 36 is secured to the front portion of the machine and terminates in a converging lower end portion 37 from which a nozzle 38 is removably mounted. The portion 37 forms a rectangular duct.

The front wall 36 has an opening 39 through which the fibrous material passes to the feeding jaws 28. A hopper 40 having inclined sides at its upper end is secured to the front wall 36 and 10 communicates with the opening 39 and serves for delivering fibrous material to the machine.

For the efficient feeding of fibrous material to the nozzle 38, the jaws 28 must be moved into maximum spaced-apart or open relation when moved away from the nozzle to the vicinity of the hopper 40. The jaws must be moved into closest relative position when moved to the nozzle.

Figure 4 is a front elevation of an enlarged fragmentary portion of fixed cam mechanism which causes lateral movements of the feeding jaws 28. The cam mechanism 45 comprises a rectangular plate 46 having an endless groove or guideway 47 formed therein. The groove 47 has two vertical portions 48 and two inclined portions 49 which are connected at their upper and lower elevations by circular groove portions 50. Each guideway receives a roller 51 carried by an actuating arm 52. The arms 52 are attached to the feeding jaws 28 and are caused by the guideways 47 to move toward each other when in lower position and away from each other when in upper position.

It is to be noted that the equal length links 30 cause the feeding jaws 28 to move in parallel relation.

As shown in Figure 3, the mounting plate 11 has apertures 55 serving to receive bolts 56 upon which are mounted a plurality of the fixed cam plates 46. The cam plates 46 are mounted in spaced-apart relation by bushings 57. The bushings 57 are of suitable thickness to provide clearance space so that the actuating arms 52 may freely move between the cam plates 46.

It is to be noted that each roller 51 is of a diameter permitting rotatable contacting relation within one of the guideways 47. In operation, when the roller 51 reaches the lower curved end 50 of the guideway, it contacts a vertically movable pawl 59 which is resiliently pressed in the direction of the guideway by a coil spring 60.

The portion of the pawl 59 which extends into the guideway is angularly directed to permit the roller 51 to continue its motion through the guideway 50. When the roller 51 reaches the angularly directed portion of the pawl 59 it forces the pawl out of the guideway against the pressure of the spring 60. When the roller 51 passes the pawl 59, the pawl is pushed by the spring into the guideway and contacts the roller and prevents its movement in a reverse direction. A pin 61 is fixed in the pawl 59 and is slidably mounted in a slot 62 in a fixed central portion 63 of the cam mechanism 45. This arrangement limits the movements of the pawl 59 into and out of the guideway 47.

It is to be noted that the filling machine 10 contains four identical inverted U-shaped frames 13, each frame having an elongated extension 25. The filling machine 10 contains four identical cams 20 and eight fixed cam mechanisms 45.

In operation, when the highest point of a cam 20 reaches the contact point on one of the resiliently supported frames 13 the frame is then in its lowermost position and is suddenly released.

The springs 15 then raise the frame 13 to its uppermost position.

It is to be noted that the fixed cam mechanisms 45 function when the gripping and feeding jaws 28 are in their lowermost position to permit the springs 15 to raise the frames 13. The fixed cam mechanisms 45 also function when the frames 13 are in their uppermost position to permit the cams to lower the frames.

It is also to be noted that the filling machine 10 comprises suction means (not shown), which in practice is suitably connected to pipes or conduits 65, through which suction is brought to bear on the machine 10 from opposite sides. The conduits are adapted to be connected to suction creating means.

It is also to be noted that the pipes 65 connect with apertures 66 at the mid-portion of the machine and between the gripping and feeding jaws 28. Screens 67 are suitably fastened in the apertures 66, to prevent the filling material from being sucked into the pipes 65.

The gripping and feeding jaws 28 feed successively into the duct 37 and into a casing such as a doll's leg 68.

In accordance with the patent statutes I have described and illustrated the preferred embodiment of my invention, but it will be understood that various changes and modifications can be made therein without departing from the spirit of the invention as defined by the appended claims.

I claim:

1. In a reciprocable gripping and feeding mechanism for fibrous material, a mounting plate, an inverted U-shaped frame slidably mounted on said plate and having upright arms, a cam in operative engagement with said frame for moving said frame downwardly, spring means for raising said frame when released by said cam, bars respectively carried by two links pivotally mounted on each arm of said frame, said bars and said arms comprising jointed structures of parallelogram formation whereby said bars are constrained to move parallel to said arms, vertical guideway means for maintaining the parallel relation of said bars during the downward and upward strokes, the distance between said bars being varied at the uppermost and lowermost ends of each stroke, said bars having feeding jaws at their lower portions, said jaws having aligned feeding teeth, each of said teeth having a horizontal side and a downwardly converging side, said teeth being adapted to feed only in a downward direction, and a nozzle mounted on said plate and in alignment with said feeding jaws, said mechanism comprising separate cam means for varying the distance between said bars and arms.

2. In a reciprocable gripping and feeding mechanism for fibrous filling material, a mounting, a housing secured to said mounting, an inverted U-shaped frame slidably mounted in said housing and having elongated arms, a cam in operative engagement with said frame for moving said frame in feeding direction, spring means for returning said frame when released by said cam, bars respectively carried by two links pivotally mounted on each arm of said frame, said bars and said arms comprising jointed structures of parallelogram formation whereby said bars are constrained to move parallel to said arms, vertical guideway means for maintaining the parallel relation of said bars during the downward and upward strokes, the distance between said bars being varied at the uppermost and lowermost ends

of each stroke, said bars having feeding jaws at their free end portions, said jaws having aligned feeding teeth, said jaws being mounted to move vertically in parallel planes and in parallel relation, a duct circumscribing said feeding jaws, a 5 screened conduit at each side of said housing and positioned intermediate said feeding jaws, a nozzle secured to said duct and centrally of said feeding jaws, said mechanism comprising separate cam means for varying the distance between said bars and arms.

MAX GOLDBERG.
